UNITED STATES PATENT OFFICE.

PETER JACOBSON, OF MILWAUKEE, WISCONSIN.

RAILWAY AIR-BRAKE DRAIN-CUP.

SPECIFICATION forming part of Letters Patent No. 680,830, dated August 13, 1901.

Application filed March 5, 1901. Serial No. 49,671. (No model.)

To all whom it may concern:

Be it known that I, PETER JACOBSON, a citizen of the United States, and a resident of Milwaukee, in the county of Milwaukee and State of Wisconsin, have invented certain new and useful Improvements in Railway Air-Brake Drain-Cups; and I do hereby declare that the following is a full, clear, and exact description thereof.

10 My invention has for its object to provide simple, economical, and readily-separable drain-cups, of the kind utilized in railway air-brake equipment between each car-section of train-pipe and a triple valve, said invention consisting in certain peculiarities of construction and combination of parts hereinafter particularly set forth with reference to the accompanying drawings and subsequently claimed.

20 Figure 1 of the drawings represents a longitudinal section of a drain-cup in accordance with my invention coupled to train and triple-valve pipes, the plane of the view being indicated by dotted line 1 1 in the second figure. Fig. 2 of said drawings represents a detail front elevation of one of the cup-sections having a strainer therein, partly broken away, the coupling-bolts appearing in this view being in section on the plane indicated by dotted line 2 2 in the first figure.

25 Referring by letter to the drawings, A B represent two sections of a cylinder embodied in my improved drain-cup, the meeting ends of these cylinder-sections being 35 annularly flanged, as herein shown. A packing-gasket C is interposed between the flanges b c of the cylinder-sections of the cup, and by means of nuts d, run on bolts e, extending through said flanges and interposed gasket, this joint of said cylinder-sections is made 40 air-tight.

The head of cylinder-section A of the cup is provided with a nipple f, with which a triple-valve pipe D has screw-thread union, 45 and a branch E of a car-section of train-pipe is likewise coupled to a nipple g, with which the other cylinder-section B of said cup is provided.

50 Arranged in the cylinder-section A of the cup is a perforate diaphragm F of preferably coarse-mesh strainer material, and be-

tween this diaphragm and a strainer-diaphragm G of very fine mesh is a mass H of sponge or other suitable absorbent material, this fine-mesh strainer being made to fit an 55 annular recess h in the flanged end of said cylinder-section of the cup flush against the packing-gasket C aforesaid. The fine-mesh strainer-diaphragm intercepts the greater portion of gritty impurities with the air passing 60 through the cup from the train-pipe to triple valve, the very minute particles of such impurities and moisture with said air being caught by the absorbent material H between said fine-mesh diaphragm and 65 coarse-mesh diaphragm F, the sole function of this coarse-mesh diaphragm being to prevent displacement of said absorbent material without interference with the flow of said air.

The particles of gritty material separated 70 from the air by fine-mesh strainer G accumulate in the cylinder-section B of the cup, and this cup being separable the accumulation may be readily removed and the strainer, absorbent material, and diaphragm contents 75 of cylinder-section A of said cup as readily cleaned whenever necessary or desirable.

Having thus described my invention, what I claim as new, and desire to secure by Letters Patent, is—

80 A railway air-brake drain-cup comprising a separable cylinder having opposite head-nipples attachable to train and triple-valve pipes, and an air-strainer consisting of a coarse-mesh diaphragm, a backing of absorbent material and a fine-mesh diaphragm back of the absorbent material all confined in the triple-valve pipe-section of the cylinder, the whole of the train-pipe section of said cylinder being in rear of the fine-mesh diaphragm 85 and constituting an accumulator for gritty particles separated from air in its passage from one to the other of said pipes.

90 In testimony that I claim the foregoing I have hereunto set my hand, at Milwaukee, in 95 the county of Milwaukee and State of Wisconsin, in the presence of two witnesses.

PETER JACOBSON.
